CLAIM

The ornamental design for a filmless insulating floor/wall panel, as shown and described.

DESCRIPTION

FIG. 1 is a front perspective view of one embodiment of the filmless insulating floor/wall panel in accordance with my design;

FIG. 2 is a top view of the filmless insulating floor/wall panel of FIG. 1;

FIG. 3 is a side view of the filmless insulating floor/wall panel of FIG. 1;

FIG. 4 is an end view of the filmless insulating floor/wall panel of FIG. 1;

FIG. 5 is a back view of the filmless insulating floor/wall panel of FIG. 1;

FIG. 6 is a front perspective view of another embodiment of the filmless insulating floor/wall panel in accordance with my design;

FIG. 7 is a top view of the filmless insulating floor/wall panel of FIG. 6;

FIG. 8 is a side view of the filmless insulating floor/wall panel FIG. 6;

FIG. 9 is an end view of the filmless insulating floor/wall panel of FIG. 6;

FIG. 10 is a back view of the filmless insulating floor/wall panel of FIG. 6;

FIG. 11 is a front perspective view of another embodiment of the filmless insulating floor/wall panel in accordance with my design;

FIG. 12 is a top view of the filmless insulating floor/wall panel of FIG. 11;

FIG. 13 is a side view of the filmless insulating floor/wall panel of FIG. 11;

FIG. 14 is an end view of the filmless insulating floor/wall panel of FIG. 11; and,

FIG. 15 is a back view of the filmless insulating floor/wall panel of FIG. 11.
